United States Patent Office.

JAMES WRIGHT, OF NEW YORK, N. Y., ASSIGNOR TO HIMSELF AND FRANCIS BLESSING, OF SAME PLACE.

Letters Patent No. 65,715, dated June 11, 1867.

IMPROVEMENT IN DEVICES FOR CLEANING THE TRAPS OF WATER-CLOSETS.

The Schedule referred to in these Letters Patent and making part of the same.

TO ALL WHOM IT MAY CONCERN:

Be it known that I, JAMES WRIGHT, of the city, county, and State of New York, have invented a new and improved Device for Cleaning the Traps of Water-Closets; and I do hereby declare that the following is a full, clear, and exact description thereof, which will enable others skilled in the art to make and use the same, reference being had to the accompanying drawing, forming a part of this specification.

The drawing represents a side view partly in section of my invention.

This invention relates to a device for cleaning the curved or S-shaped pipe or traps of water-closets, and consists in the use of a flexible rod, (or series of rods hinged together,) which is inserted in the end of the pipe and can accommodate itself to the shape of the tube, so as to clean the same completely. Heretofore great difficulty used to be experienced in the cleanining of these curved pipes, and much time was lost in the attempt to satisfactorily do it. By my invention the work is made very easy, as the flexible rod will adapt itself at once to the curve of the pipe, and will therefore at once remove any material that may have accumulated in the same.

A represents the trap of a water-closet. B is a straight tubular guide, which, when the trap is to be cleaned, is set upon the end of the pipe A, as shown. C is a straight metal or other rod, having a handle, D, on its upper end. E E are small metal bars, which are connected one to another so as to form a long flexible bar, one end of which is pivoted to the lower end of the rod C. In each joint, between the bars E E and C, may be arranged a friction-roller, F, the diameter of which should be larger than the width of any of the bars E. The flexible rod is passed through the tube B into the pipe A, and when pushed down the links E E will be carried through the windings of the pipe A, in the manner shown in the drawing. The rollers F will serve to make the parts move easier around the corners in the pipe A. Without the guide B this rod could not be used, as the flexible portion must be longer than the first straight portion of the pipe A, and would therefore project above the same, and would be folded together if an attempt were made to push it down into the trap. In the tube B the flexible rod is always kept straight, and can be easily managed by the inflexible handle C D.

I claim as new, and desire to secure by Letters Patent—

1. The flexible rod E, when made as described, in combination with the tubular guide B and inflexible handle C D, all made and operating substantially as and for the purpose herein shown and described.
2. The friction-rollers F, in combination with the links E of the flexible rod and with the handle C D, all made and operating substantially as herein shown and described.

JAMES WRIGHT.
